UNITED STATES PATENT OFFICE.

HARRISON B. WALTER, OF PHILADELPHIA, PENNSYLVANIA, ASSIGNOR TO FIBRE CONTAINER COMPANY, A CORPORATION OF PENNSYLVANIA.

SWINGING TABLE.

Application filed August 26, 1920. Serial No. 406,138.

To all whom it may concern:

Be it known that I, HARRISON B. WALTER, a citizen of the United States, and a resident of the city of Philadelphia, county of Philadelphia, State of Pennsylvania, have invented certain new and useful Improvements in Swinging Tables, of which the following is a specification, reference being had to the accompanying drawing.

10 My invention relates to a support in the nature of a swinging table for supporting paper or pasteboard cartons adapted to be operated upon by adjacently located multiple stapling machines, such machines operating together to drive staples in two adjacent sides of a carton in one operation, the swinging table being of use to carry and hold the carton in position during such operation and to permit the ready shift and 15 rotation of the carton to present the other two sides for stapling after the first two sides have been stapled.

Among the objects of the invention is to provide simple and conveniently operated 20 means for supporting an article, such as a carton, opposite a duplex type of multiple stapling machine whereby the carton may be manually readily moved into place, stapled by the machines, moved away from the 25 machine, turned around and again presented to the machine for completion of the stapling operation.

Another object is to construct or provide a means whereby a carton may be stapled at 30 one end thereof when empty to attach one of the heads of the carton prior to the attaching of the other head.

Another object is to provide a similar means to the one above mentioned for supporting the carton in position for stapling the head at the other end when the carton is filled with goods, such as canned goods and like material.

Another object is to construct the device 40 so that the same may be adapted to different sizes of cartons within a certain range of sizes, without necessitating the use of different size devices each time a different size carton is to be stapled.

50 Certain other objects and advantages of my invention will more fully appear herein-after.

Referring to the drawing, I have shown one form of device constructed in accordance with my invention, in which—

Fig. 1 shows a view in elevation of a device constructed in accordance with the invention, with a carton in section and in position to be operated upon;

Figs. 2 and 3 are top plan views of multiple stapling machines shown with a swinging table and a carton (both shown in dotted lines) in two positions of operation;

Fig. 4 is a view, in elevation, of a means for supporting a carton when the first head 65 of the carton is in place for stapling, the carton being shown in section; and

Fig. 5 is a top plan view of the device, shown in Fig. 4, with the carton shown in horizontal section.

Referring more particularly to the drawing, the invention, as shown thereon, comprises a pillar 1 to which is connected a bracket 2 adapted to be vertically slidable on the pillar 1 as well as angularly rotatable 75 about the axis thereof. For the purpose of supporting the bracket in operative position, the pillar 1 may be provided with a supporting collar 3 adapted to be secured in any adjusted position on the pillar 1 by means of a set screw 4. The bracket comprises a horizontal flat member 5, a vertical member 6 provided with flanges at both ends thereof, and an oblique member 7 also provided with flanges at the ends thereof, and all connected together to form, in general, a right triangular bracket. One end of the member 5 and a flange of the member 7 may be secured together by means of a pivotal bolt 8, the other flange of the member 7 and a flange 80 of the member 6 secured together by a pivotal bolt 9 and the other end of the member 5 and the other flange of the member 6 secured together by a pivotal bolt 10, both bolts 9 and 10 being coaxial.

At the upper part of the bracket 2 and suitably pivotally secured thereto by means of the bolt 10, is provided a swivel collar 11 adapted to slide along and rotate relative to the pillar 1 and to rest upon the collar 3, the collar 11 being provided with a laterally extending lug pivotally connected to the bolt 10. Similarly, at the lower end of the bracket 2 is provided a second swivel collar 12 also slidable along

and rotatable about the pillar 1 and also provided with a laterally extending lug pivotally connected to the bolt 9.

At the free upper end of the bracket 2 may be secured a plate 13, of generally sector form, adapted to act as a support for the means upon which the carton rests. This plate may be provided with an elongated slot 14 near one end thereof, longitudinally disposed with respect to the length of the plate 13 and at the other end thereof with an arcuate slot 15, while intermediate of the above-mentioned slots may be provided an aperture 16 adapted to receive the bolt 8 and about which the plate 13 is adapted to rotate to the extent permitted by the slot 15. A bolt 17, suitably secured to the plate 5 and passing loosely through the arcuate slot 15, is of use to permit relative angular movement of the plate 13 thereto about the bolt 8 as a pivot or axis. Through the slot 14 extends a pivotal bolt 18, suitably secured to the plate in any adjusted position along said slot. The bolt 18 may be provided with an upwardly extending bearing pin 19, which may be preferably rounded at its upper end, said pin acting as a pivot or axis for the rotation of the carton support and the carton as will appear more fully hereinafter. Above this pin is rotatably supported a rotatable supporting plate 20, which may be provided with a depending central hub 21, suitably bored or recessed to form a socket at its lower end to receive the upper end of the pin 19. If desired, a bearing plate or piece 22, of relatively hard metal, may be inserted at the bottom of the recess or socket to bear against the rounded end of the pin 19, thereby providing a durable wearing surface having minimum friction. The plate 20 is so shaped as to provide a plurality of arms in which are provided slots 23 and 24 radially disposed with respect to the axis of the pin 19 and upon opposite sides thereof, and slots 25 and 26 disposed in lines perpendicular to each other and spaced from said axis also on opposite sides thereof. In other words, the plate may be regarded as having a generally rectangular shape, with the slots provided at the corners thereof, with two slots disposed along the diagonal of the plate, and the other two slots perpendicular to each other and oblique to the other slots of the plate. The purpose of these slots is for adjustment of the parts used in supporting and holding different size cartons in place as will more fully appear hereinafter.

Upon the plate 20 may be provided a plurality of blocks 27, 28, and 29, each block being suitably secured in place by means of bolts 30, 31 and 32 passing through the respective slots 25, 24 and 26, said bolts being adapted to be adjustably secured at any point along said slots. Each block is

also adapted to be rotated about its respective bolts to the position desired when fitting a carton in place. Each block may be also provided with a recess or socket 33 for the purpose of receiving a head 34 of any of the bolts 30, 31, or 32 in order that the top of the head will lie beneath the top surface of the block 27, 28 or 29 as the case may be. It will be observed that each of these blocks is of rectangular form with the perforations 75 through which the bolts pass near one end thereof so that when the block is secured in position it will be presented to the flanges of the head 35 of a carton 36 at the corners thereof. As for example, it will be noted 80 that in Figs. 2 and 3 a small carton is in position whereby the long sides of the blocks are disposed in such a manner as to provide for the positioning or overlapping there-over of the flanges of a head 35 of a carton, the blocks being at their outward extended position along the slots 25, 24 and 26. If, however, a larger carton is to be used, the blocks 27, 28 and 29 may be turned substantially at right angles to the positions 85 now shown so that the other ends of said block may extend at a greater distance from the supporting plate, in order to receive the head of a larger carton. If the carton be of an intermediate size or smaller than that 90 shown in the figures shown upon the drawing, it is obvious in either of the positions of the blocks the same may be moved inwardly along their respective slots to the size where the blocks are properly positioned 100 to receive the particular size head of the carton used.

Referring now more particularly to Figs. 4 and 5, it will be noted that the plate 20 is further provided upon its upper side with 105 a central hub 37 having a screw threaded socket adapted to receive a bolt or screw 38. This supporting means is for the purpose of securing thereto a frame or crate 39 usually and preferably made of strips and pieces of wood and of the proper size and formed to receive the four walls of a carton. In the figures shown, this frame comprises vertical strips of wood 40, 41, 42, 43, 44, 45, 46, and 47, joined in pairs at the corners of 110 the structure, each corner being cut or beveled at the upper ends thereof with a taper 48 for the purpose of facilitating the insertion of the carton tube or body over the frame as will be obvious from the illustrations shown in Figs. 4 and 5. The frame or crate may also be provided with a transverse bottom member 49, a transverse top member 50 rigidly secured to the side pieces in any well known and suitable manner. 115 The bottom 49 may be rigidly secured to the hub 37 by means of the bolt or screw 38, the upper end of the frame including the member 50, acting as a supporting means upon which may rest a head 35' of the carton in 120 125

proper position for the stapling of the flanges 51 thereof and the end portions 52 of the walls of the carton.

In order that the side walls of the carton 5 may be properly positioned when first placed upon the frame 39, the plate 20 may be provided with supporting members 53 which may be secured to the plate 20, in lieu of the blocks 27, 28 and 29, by means 10 of bolts 54 passing through suitable apertures in the plates 53 and the slots 25, 24 and 26 of the supporting member 20. The plates 53 may be adjusted both in said slots as well as about the axis of the bolts securing 15 the same to the supporting member 20, so that the members 53 may project sufficiently beyond the plate 20 for the contact thereof with the lower end of the carton body or tube, as is fully shown in Figs. 4 20 and 5.

The pillar 1 is usually attached to a duplex type of multiple stapling machine, such machine being conventionally shown upon the drawing. Such machine may comprise 25 two multiple stapling machines A and B placed at right angles to each other so that the stapling elements thereof may operate at the same time upon two adjacent sides of a carton. The pillar may be supported with 30 the ends thereof rotatably mounted in the socket members 55 and 56 respectively secured to an upper portion 57 and a lower portion 58 of one of the stapling machines by means of screws 59 and 60 as is clearly 35 shown in Fig. 1.

In operation, the parts of a carton usually are three in number, namely, a square or rectangular tubular portion, having previously been made from a strip of material 40 suitably bent to form a square or rectangular tube and with the overlapping ends of one side thereof previously stapled, and the flanged heads 35 and 35'. The tube is usually placed over a frame 39 until one end of 45 the tube contacts with the members 53 on the supporting member 20. The other end of the tube will project above the top surface of the top 50 of the frame a distance equal to the width of the flange 51 of the head 35' 50 of the carton. The head 35' is then inserted in position in the upper end of the tube of the carton with the wall or bottom of the head resting upon the member 50. The operator then moves the supporting means, 55 including the member 20, pivotally mounted upon the pin 19 carried by the bracket 2, about the axis of the pillar 1 and turns the carton 36 and the frame 39 about the axis of pin 19 to properly present two adjacent 60 faces of the upper end of the carton opposite the two rows of stapling mechanism on the machines A and B. After the stapling operation is performed, the carton and the frame, with the mechanism supporting the 65 same, are moved from the position shown in

Figs. 1 and 2 to the position shown in Fig. 3 and is rotated about the axis of the pin 19 so as to bring the opposite faces into position to be presented for stapling operation, the operator then moving the carton and the 70 supporting means towards the stapling machines where a second stapling operation on the opposite faces occurs.

After the cartons have been thus provided with heads at one end thereof, the same, at 75 any time desired, may be inverted and filled with canned goods or other commodity, as the case may be, to a point short of the open end of the carton. The cartons so filled may be successively placed upon the supporting 80 means provided with the spacing blocks 27, 28 and 29, instead of using the plate members 53, and then the heads 30 inserted in place in the open end of the cartons so as to cause the bottom of the 85 heads to rest upon the material included in the cartons and to bring the flanges thereof opposite the end portions of the cartons, as was done in inserting the other heads in the other end of the cartons. With the parts of 90 a carton now in place upon the supporting means, the operator can swing the same from the position shown in Fig. 3 to that shown in Fig. 2 wherein the stapling mechanism of machines A and B will substantially simultaneously operate upon two sides of the carton to staple the flanges of the head 35 thereto. The operator then moves 95 the carton from the stapling means angularly about the axis of the pillar 1, rotates 100 the carton and its support about the axis of the pin 19 and then moves the same toward the machines to present the unstapled sides of the carton thereto for final 105 stapling operation. At this point the stapling operation is completed. The carton then may be filled or removed from the supporting means and another carton filled with the commodity raised to its place and the 110 operation continued as above indicated.

The invention herein described has reference to means adapted for use with stapling machines of the type disclosed in my U. S. Letters Patent No. 1,357,534, granted Nov. 2, 1920, No. 1,378,390, granted May 17, 115 1921, No. 1,417,704, granted May 30, 1922, No. 1,418,853, granted June 6, 1922, No. 1,420,227, granted June 20, 1922, No. 1,440,641, granted Mar. 27, 1923, and No. 1,458,161, granted June 12, 1923.

While I have herein described and shown upon the drawings one form of device or means for carrying out my invention, it is to be understood that the latter is not limited to the particular details and arrangement of parts shown and described, but that the same comprehends other forms and arrangements as do not depart from the spirit of the invention and the scope of the appended claims.

Having thus described my invention, what I claim and desire to protect by Letters Patent of the United States is:

1. In a device of the class described, the combination of a pillar, a bracket mounted upon said pillar angularly reciprocable about the axis thereof, an angularly adjustable member mounted on said bracket, means for securing said member in operatively rigid relation with the bracket, a pivot pin secured to said member and adapted to be moved therewith upon the adjustment of said member relative to said bracket, a support rotatably mounted upon said pivot pin and having a plurality of slots extending in different directions and means adjustable in said slots for holding different size objects in position on said support.
2. In a device of the class described, the combination of a pillar, a bracket mounted upon said pillar angularly reciprocable about the axis thereof, an angularly adjustable member mounted on said bracket, means for securing said member in operatively rigid relation with the bracket, a pivot pin adjustably secured to said member and adapted to be moved therewith upon the adjustment of said member relative to said bracket and for independent adjustment relatively to the member, a support rotatably mounted upon said pivot pin and provided with radially and transversely located slots, and positioning means slidably adjustable in said slots to fit different sized objects supported upon said support and adapted to be secured to said support in adjusted position.
3. In a device of the class described the combination of adjustable supporting means,

a member angularly movable on said adjustable supporting means, an angularly adjustable member mounted on said angularly movable member, a pivotal member mounted on said angularly adjustable member and longitudinally adjustable with respect thereto, rotatably mounted means on said pivotal member having a plurality of slots extending in different directions, and means adjustable in said slots for positioning an object to be operated upon on said rotatably mounted means.

4. In a device of the class described the combination with a supporting pillar, of a bracket supported by and angularly rotatable about said pillar, a plate pivoted on the bracket and provided with an arcuate slot on one side of the pivot and a longitudinally extending slot on the other side of the pivot, means extending through said arcuate slot for clamping said plate in operatively fixed adjusted position with respect to the bracket, pivoting means longitudinally adjustable in and extending through the other slot, a supporting member pivoted on said pivoting means and provided with a pair of radially directed slots disposed on opposite sides of the pivot and a pair of slots disposed substantially normal to each other and each in angular relation with the first mentioned slots, clamping means extending through and adjustable in each of the slots, and positioning means carried by each of the clamping means and adapted to be secured by the clamping means in adjusted relation with the support.

In witness whereof, I have hereunto set my hand this 25th day of August, 1920.

HARRISON B. WALTER.
